G. M. TURNER

CENTRIFUGAL PROCESS OF BLENDING OIL AND GAS

Filed May 7, 1920

UNITED STATES PATENT OFFICE.

GEORGE M. TURNER, OF RIVERSIDE, CALIFORNIA.

CENTRIFUGAL PROCESS OF BLENDING OIL AND GAS.

Application filed May 7, 1920. Serial No. 379,582.

To all whom it may concern:

Be it known that I, GEORGE M. TURNER, a citizen of the United States, residing at Riverside, in the county of Riverside and 5 State of California, have invented certain new and useful Improvements in Centrifugal Processes of Blending Oil and Gas, of which the following is a specification.

This invention relates to the extraction 10 of gasoline from gases and vapors, and particularly from natural gas, and pertains to the use of an absorbing oil for extracting the gasoline content of gas.

One object of the invention is to provide 15 an efficient and advantageous process of effecting by the use of centrifugal means, the separation of the gasoline and the absorption of the same by an absorbing medium.

20 One feature of the invention provides for the thorough blending of the gasoline and gas with the absorbing oil, and includes the process for conducting a continuous separation and absorption. The apparatus described in connection with this invention is 25 specifically described and claimed in my copending application Serial No. 434,894.

Details of these and other features provide 30 for the use of centrifugal force for effecting quickly such thorough blending and provide details of construction of centrifugal apparatus whereby the blending process is conducted.

The present invention is to be differentiated 35 from current processes which require the use of relatively large apparatus, large absorbing surfaces, and the use of mineral seal oil and pressures ranging up to several hundred pounds. The present construction provides for the relatively rapid mixing of the absorbing oil with the gaseous medium by the use of centrifugal force, which force also provides a very considerable portion of the necessary pressure.

40 The operation of the process and the details of construction are explained in the following specification, claimed in the accompanying claims, and illustrated in the drawing which forms a part of this application.

Referring to the drawing, Figure 1 is a vertical section through the centrifugal blending apparatus,

Figure 2 is a sectional view, partly 55 broken away on the line 2-2 of Figure 1,

looking down on the rotor member, and

Figure 3 is an exterior view with a portion of the casing broken away and illustrating the relative position of the interior parts of the apparatus.

Referring in detail to the constructions illustrated in the drawing, 1 is the main casing which is substantially circular horizontally. Extending through the center of the casing 1 and vertically, is a drive shaft 2 having at its lower end a fixed pulley 2^a which is driven by a belt 2^b from a source of motive power 2^c, which is illustrated as an electric motor. The shaft 2 is journaled in the casing 1 at the points 3, and is provided with suitable stuffing boxes or packing glands 4, which latter assist in preventing the escape of materials along the shaft 2. The lower end of the shaft rests on a suitable base 5 and roller or ball bearing means

is provided for effecting the free movement of the shaft 2 at its lower end. The interior of the casing includes a rotor member 6 which is formed of a flat plate-like member having a substantially circular periphery and which is fixed to rotate with the shaft 2 by means of a key member 7.

The hub portion of the member 6 rests on an annular collar 8 fixed to the shaft 2 and prevents the slipping of the rotor member 6 along the shaft. On the upper and under faces of the rotor member 6 are flange members 9 which extend radially and project substantially at right angles from the opposite faces of the member 6.

These flanges are secured to the rotor member by any suitable means, such as welding, as indicated at the point 10. The hub ends of the flanges 9 are secured to a perforate member 11 which encircles the shaft 2 and which likewise is rigidly secured to the rotor member. The outer ends of the flange members 9 are secured by the circular plate members 12, which are likewise fastened to the rotor member, and which are freely

perforated with the openings 13. The flanges 9 on one side of the plate-member 6 are staggered with respect to those on the opposite side, and all the flanges are very rigidly secured by means of their fastenings to the members 11, 6 and 12.

Projecting outwardly from the ends of the flange members 9 and beyond the member 12 are the radially extending agitating arms 14, which are rigidly secured for rotation

105 110

with the rotor member 6 and the flanges 9. These agitating arms 14 may be struck up from the part 12 or may be additional flanges or arms rigidly secured to the flanges 9 or the member 12. Positioned immediately at the periphery of the rotor member 6 and spaced from the inner wall of the casing 1 is a filter screen member 15 which closely embraces and encircles the periphery of the rotor member. Fixed baffles or agitating arms 16 are secured to the screen member 15 and are positioned in staggered relation with respect to the movable arms 14. Brace members 17 extend from the inner wall of the casing 1 and constitute fastening means and spacing means for securing the filter member 15 in fixed relation to the casing 1 and the rotor member.

Pipe means for the introduction of an absorbing oil is indicated at 18, and a control valve for regulating the entry of oil is indicated at 18^a. Pressure means for the supply of oil is diagrammatically represented by the pump 18^b. Natural gas under pressure, or other gasoline, or kerosene containing gaseous or vaporous medium, is led into the casing through a pipe 19 having the control valve 19^a and a pressure pump 19^b. An outlet for oil and gas is indicated 30 by the pipe 20, which has a suitable control valve 20^a. A pressure gage is indicated at 21.

The operation of the process and apparatus will be understood from the following. Sufficient oil is admitted and the apparatus is started by turning on the motor 2^c and rotating the shaft 2 with its rotor member 6 and parts secured thereto. The action of these revolving parts generates considerable centrifugal force and throws the absorbing oil, which may be mineral seal oil, or other satisfactory absorbing medium, toward the outer wall of the casing 1. As the absorbing oil is admitted, this centrifugal force will bank up the oil, filling the space between the casing 1 and eventually covering the periphery of the rotor member 6. During this banking up process the oil coming into contact with the agitating arms 14 and 16 is subjected to a very severe agitating treatment. Natural gas under pressure is forced in through the pipe 19, and with sufficient pressure to overcome the centrifugal force acting on the oil at the periphery of the rotor member, and with sufficient force to be bubbled through the filter member 15 in the lower half of the casing and to be forced back through the filter member on the upper side of the casing, and finally to escape out through the pipe 20. The entering pressure of the gas and oil must exceed the centrifugal effect of rotation in order that the materials may flow from the outer portion of the casing axially toward the outlet pipe 20. The agitation provided by the arms 14

and 16, and the rapidly revolving rotor member with its flanges 9, serves to thoroughly break up the oil and to mix the oil with bubbles of gas, and the oil which eventually flows out of the pipe 20 carries with it these bubbles. The solubility of the gas in the oil depends in part on the pressure provided, and there develops a speed of rotation which may be considered with the pressure under which the absorbing oil and gas are admitted. The final governing control for the pressure is the valve 20^a, which may be set to vary the outflow of oil and gas. If this valve is wide open, there will be but little pressure within the apparatus, but on the other hand, if this valve is partly closed, the pressure within the apparatus is correspondingly built up. The agitation due to the centrifugal action, the force of the flanges 9, the agitating arms 14 and 16, and the screen 15 serves to break the gas bubbles to a relatively small size and promotes the solubility of the material carried by the gas in the absorbing oil.

The apparatus requires no heat and the absorption is conducted most advantageously if the conditions are maintained at a fairly low temperature, the absorption of the gas by the oil being correspondingly promoted. The modifications of the apparatus may be made without departing from the essential features of the process which require the use of centrifugal force and rapid agitation. For instance, the apparatus need not necessarily be positioned to revolve on the vertical axis, the natural gas and oil may be admitted through one or any number of pipes or openings in the casing, and one or more outlets may be provided for the outlet of material. Likewise, the process is not dependent on the position of the inlet or outlet openings of the material, and might well be conducted if these materials were admitted at the outer wall of the casing, or tangentially.

After the absorption of the gasoline content of the gas by the absorbing oil the material may be subjected to the usual separation processes, such as distillation, for removing the gasoline from the absorbing oil. It is believed that the use of this process and centrifugal apparatus in which it may be conducted will provide effective means of treating gasoline-carrying gases and vapors with an absorbing oil much more quickly, and to far better advantage than has heretofore been possible.

I claim:—

1. The process of extracting gasoline from natural gas, which process comprises maintaining by the application of centrifugal force a banked up body of absorbing oil under centrifugal pressure within a casing, forcing gas containing gasoline to bubble through said banked up oil with sufficient

pressure to overcome the centrifugal force applied to the oil, and separating the gasoline content from the absorbing liquid.

2. The process of extracting gasoline from natural gas, which process comprises maintaining by the application of centrifugal force a banked up body of absorbing oil under centrifugal pressure within a closed casing, forcing gas containing gasoline to bubble through said banked up oil with sufficient pressure to overcome the centrifugal force applied to the oil, and subjecting the oil with its absorbed gasoline content to distillation to separate the gasoline from the oil.

3. The process of separating gasoline from natural gas, which process comprises passing such a gas into a casing containing a gasoline absorbing oil, subjecting said gas and oil to combined centrifugal force and agitation by the action of a rapidly revolving rotor member, causing the oil to bank up within said casing and to cover the periphery of said rotor member, maintaining under the pressure of centrifugal force the oil material thus banked up, forcing the gas through the oil so banked up, removing the resultant gases and liquid materials, and separating gasoline from such resultant liquid material.

4. The continuous process of separating gasoline from natural gas containing gasoline, which process comprises continuously

passing such a gas into a casing containing a gasoline absorbing oil, continuously subjecting said gas and oil to combined centrifugal force and agitation by the action of a rapidly revolving rotor member, maintaining a bank of the oil under centrifugal force, passing the gas containing gasoline through the oil with sufficient pressure to overcome the centrifugal force under which the oil is banked up, continuously removing the resultant gaseous material and the liquid material, and separating gasoline from such resultant liquid material.

5. The continuous process of separating gasoline from natural gas containing gasoline, which process comprises continuously passing such a gas into a casing containing an absorbing oil, continuously subjecting said gas and oil to combined centrifugal force and agitation by the action of a rapidly revolving rotor member, continuously causing the oil to bank up within said casing and to thus fill the space between said casing and the periphery of said rotor member, maintaining the oil thus banked up under the pressure of the applied centrifugal force, continuously forcing the gas through the oil so banked up with sufficient pressure to overcome the pressure under which the oil is maintained, and continuously removing the resultant gaseous and liquid materials.

In testimony whereof I affix my signature.
GEORGE M. TURNER.
